Attorney

UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

BUSHING-INSULATOR TERMINAL.

Application filed August 2, 1922. Serial No. 579,138.

This invention relates to means for securing the conductor at the end of an insulator bushing to the bushing itself and to the conductor lead extending away from the bushing. The invention has for its object the provision of a terminal which shall effectively close the end of the bushing, which shall provide a low resistance contact between the conductor and the lead wire, which shall be convenient to install and which shall be of improved construction and operation.

The invention is exemplified in the combination and arrangement of parts shown in the accompanying drawings and described in the following specification and it is more particularly pointed out in the appended claims.

In the drawing, numeral 10 designates the outer end of a dielectric bushing such as is used for insulating conductors from transformer housings, switch housings, roofs, walls or other devices through which a conductor passes and from which it is insulated. Conductor (11) extends through the bushing (10) and is provided with a terminal lug (12), soldered, brazed or otherwise secured to the end of the conductor. A cap (13) is secured to the end of the bushing (10) by cement (14) in a well known manner. A flange (15) extends upwardly from the cap (13) and is provided with a tapered socket (16) for receiving a correspondingly tapered or conical bushing (17). The bushing (17) is screwed onto a threaded portion (18) at the end of the terminal lug (12). An angular socket (19) is provided in the cap (13) for receiving a correspondingly shaped portion (20) at the lower end of the lug (12) by means of which the lug (12) and the conductor (11) are held against rotation in the cap (13). The outer end of the lug (12) is provided with a tapped opening (21) for receiving an eye or other connection, for a cord or line by means of which the conductor (11) may be drawn through the bushing (10) and the opening in the flange (15). After the lug (12) is brought into the opening in the flange (15) the conical bushing (17) is screwed into place on its threaded end (18) to hold the conductor in position in the bushing. A lead wire (22) is provided with a terminal member (23) properly secured to the end of the lead wire and having a contact face (24).

for engaging the end of the conductor lug (12). The face (24) is firmly clamped against the end of the conductor lug (12) to form electrical contact therewith by means of a clamping nut (25) having right and left hand threads (26) and (27) for engaging corresponding threaded portions on the flange (15) and the contact member (23) respectively. The nut (25) is provided with angular shoulders (28) for receiving a wrench or other tightening device by means of which the face (24) may be firmly clamped against the end of the conductor lug (12). This action not only brings the two abutting faces into close engagement, but presses the threads (18) of the conductor into close contact with the thread in the bushing (17) and also forces the tapered surface of the cone (17) into close contact with the tapered surface (16) on the flange (15).

The oppositely directed threads (26) and (27) operate against one another to draw their surfaces into close contact, thus establishing electrical connections from the conductor (11), through the nut (25), bushing (17) and contacting threaded surfaces. In this way a double path is provided for electrical current between the conductors (17) and (22) and the contacting surfaces are all under heavy pressure to assure low resistance electrical connections. The member (23) may be provided with a weathered shield (29) for protecting the threaded joint (27).

I claim:

1. In a dielectric bushing having a conductor extending therethru, a cap on said bushing, means for supporting said conductor on said cap at the end of said bushing, a conductor lead engaging the end of said conductor and a clamping member having oppositely directed threaded engagements with said conductor lead and cap respectively for pressing said conductor and lead into contact with one another to provide electrical connections therebetween.

2. In a dielectric bushing having a conductor extending therethru, a fitting for said bushing having a seat therein for supporting the end of said conductor, a conductor lead, and a clamping nut having oppositely directed threaded engagement with said fitting and lead for pressing said lead into contact with said conductor.

3. In a dielectric bushing having a conductor extending therethru, a fitting for said bushing having a seat for supporting said conductor at the end of said bushing, a conductor lead terminal having butt end engagement with said conductor, a clamping nut having right and left hand threads therein, said threads meshing with corresponding threads on said fitting and terminal member for pressing said terminal member against the end of said conductor and for holding said conductor in place in its seat.
4. In a dielectric bushing having a conductor extending therethru, a fitting for said bushing having a tapered seat therein, a conical bushing threaded on said conductor and fitted in said seat, a terminal member arranged to contact at the end of said conductor and a clamping nut having threaded engagement with said terminal member and fitting for clamping said terminal member against said conductor and for forcing said conical bushing closely into said seat.
5. In a dielectric bushing having a cap secured to the end thereof, a flange on said cap provided with a conical seat, a conductor extending through said bushing and having a reversely tapered portion connected therewith and fitting said seat, a conductor lead engaging the end of said conductor and means for clamping said conductor lead against said conductor to force the tapered surface of said conductor into said seat.
6. In a dielectric bushing having an opening therethru, a cap fitted onto the end of said bushing, a conductor extending through said bushing and having the end thereof threaded, interfitting means between said conductor and cap for preventing relative rotation thereof, a tapered bushing threaded on the end of said conductor and seated in said cap, a lead conductor having a terminal engaging said first mentioned conductor and a clamp engaging said lead conductor and cap for forcing said lead conductor against said first mentioned conductor to press said tapered bushing into its seat.
7. In a dielectric bushing having a conductor extending therethru, a fitting for said bushing, means for supporting said conductor in said fitting, a lead terminal, a nut having right and left hand threaded engagement with said fitting and terminal and a weather guard for protecting said threaded engagement.
8. In a dielectric bushing having a conductor extending therethru, a cap on the end of said bushing having a tapered seat therein, interfitting means for preventing rotation of said conductor in said cap, a lead conductor having contact with said first mentioned conductor and a right and left hand threaded nut for pressing the contacting surfaces of said conductors tightly together without relative rotation thereof.
9. In a dielectric bushing having a conductor extending therethru, a cap for said bushing, interfitting means for preventing relative rotation of said conductor and cap, said cap having a tapered seat therein, a conical bushing threaded on said conductor and fitted in said seat, a lead conductor terminal having butt end engagement with the end of said conductor, a nut having oppositely threaded engagement with said cap and lead conductor terminal for exerting pressure on the contact between said terminal and conductor, thus forcing said conical bushing in its seat and a weather shield for protecting the joint formed by said nut.
- In testimony whereof I have signed my name to this specification on this 29th day of July, A. D. 1922.

ARTHUR O. AUSTIN.
